(57) CLAIM

The ornamental design for a toiletries and accessories case for travel, as shown and described.

DESCRIPTION

FIG. 1 is a perspective view of a toiletries and accessories case for travel showing our new design;

FIG. 2 is a front view thereof;

FIG. 3 is rear view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines showing toiletries, zipper, zipper pulls and a hanger are for the purposes of illustrating environment and form no part of the claimed design.
